Inventor:

Florence A. Curry.

UNITED STATES PATENT OFFICE.

FLORENCE A. CURRY, OF NEWTONVILLE, MASSACHUSETTS.

VEIL-PIN OR GARMENT-FASTENING DEVICE.

No. 801,366.

Specification of Letters Patent.

Patented Oct. 10, 1905.

Application filed November 7, 1904. Serial No. 231,705.

To all whom it may concern:

Be it known that I, FLORENCE A. CURRY, a citizen of the United States, residing at Newtonville, county of Middlesex, and State of Massachusetts, have invented a new and useful Improvement in Veil-Pins or Garment-Fastening Devices, of which the following is a full and complete description.

My invention relates to veil or garment fastening devices, and is an improvement upon an invention described and claimed by me in an application for Letters Patent of the United States, Serial No. 190,688, filed January 26, 1904.

My present improvement consists in a simplification of the apparatus and in the combination, as hereinafter described, and as shown in the accompanying drawings, in which—

Figure 1 is a plan from the under side with the finger-pieces removed. Fig. 2 is a side view. Fig. 3 is a top plan showing the finger-pieces attached to or integral with the extensions as described.

I will now describe my invention.

A is a metallic base or plate carrying a holding device, such as a pin *i*, by which it may be attached to some support, and also having the upturned ears *a*, in which is journaled a rod 1. A is preferably spoon-shaped, as shown, at the extremities.

B B are leaves having projections *b b*, and C C are leaves having the projections *c c*, and at the angle formed by the bending of *b b* upon B B and *c c* upon C C are the holding-ears *f*, *f' f'*, through which also passes the rod 1.

b' b' and *c' c'*, as shown in Fig. 3, are decorative extensions of *b b* and *c c*, representing, as shown in said figure, the wings of an insect.

D in Fig. 3, representing the body of an insect, is rigidly attached to the upturned ears *a a* of the base A A, so as to be directly over the rod 1. D is omitted in Figs. 1 and 2 in order to better show the other parts.

d e are small springs coiled about the rod 1 and having their ends bearing against so as to exert pressure upon the extensions *b b c c* of the leaves B B C C. The leaves B B C C will be seen to spread out and enlarge themselves from their several extensions in such form that, as shown by Fig. 3, the leaf C C will substantially conceal the leaf B B, as shown in Fig. 3.

It will be seen from the drawings that compression of the extensions *b b*, having the finger-pieces, if desired, *b' b'*, when compressed between the fingers will necessarily

raise the plates B B, which, as shown in Fig. 2, being below the leaves C C, will necessarily raise those also. The veil or other article fastened being clasped at two points between the leaves A A and C C will thus be released. Upon compressing the finger-pieces *c c* of the extensions *c c*, however, only the leaves C C will be raised, which will release the two portions of the article held previously retained by the pressure of C C upon B B.

The operation of my veil-pin will be plain from the drawings and the foregoing description. Upon compressing between the fingers the extensions *b' b'* the plates B B will be raised and carry with them the plates C C; but upon compressing the extensions *c c* only the leaves C C will be raised. It will be seen that my improvement upon my previous invention consists, substantially, in reducing the number of rods, springs, and ears, thereby greatly simplifying and so lessening the cost of manufacture and also, by reason of the exclusion of parts, obtaining the more simple method of action.

Having described my invention, what I claim is—

1. A veil-fastener composed of a base-plate provided with two perforated holding-ears, two spring-controlled leaves carried by the base and adapted to hold a veil, an extension upon each leaf at nearly a right angle thereto, two holding-ears upon each of said leaves, a rod journaled in said holding-ears of said leaves and of said base-plate, a spring coiled about said rod its ends bearing against the extensions of each leaf, all so adapted and combined that by applying the pressure of the fingers to the extensions of said leaves the same may be elevated; substantially as described and shown.

2. A veil-fastener composed of a base-plate provided with two perforated holding-ears, four or more spring-controlled leaves, one pair superimposed above the other, carried by the base and adapted to hold a veil, an extension upon each leaf at nearly a right angle; two holding-ears upon each of said leaves, a rod journaled in said holding-ears of said leaves and of said base-plate; two springs coiled about said rod, one having its ends bearing against the extensions of one of the superimposed pair of leaves and the other spring having its ends bearing against the other superimposed pair of leaves, all so adapted and combined that by applying the pressure of the fingers to the extensions of

one pair of leaves that pair and the other pair
may be elevated, or by applying the pressure
of the fingers to the other pair of leaves only
that pair may be elevated; substantially as de-
5 scribed and shown.

In testimony whereof I have signed my name
to this specification, in the presence of two

subscribing witnesses, this 3d day of November,
1904.

FLORENCE A. CURRY.

In presence of—

FRED C. CHAMBERLIN,
MILDRED KENNEDY.
